UNITED STATES PATENT OFFICE.

JAMES E. EVANS, OF CINCINNATI, OHIO.

DESIGN FOR A FRAME FOR VOLTAIC BATTERIES.

SPECIFICATION forming part of Design No. 15,453, dated October 14, 1884.

Application filed May 26, 1884. Term of patent 3½ years.

To all whom it may concern:

Be it known that I, JAMES E. EVANS, of Cincinnati, in the county of Hamilton and State of Ohio, have invented a new Design in Voltaic-Battery Frames, of which the following is a specification.

The figure in the drawing shows a plan view of my design of a frame of a voltaic battery.

The leading feature in the said design is the horseshoe shape of the frame A, and its rims B and C, having dovetail shapes b and c on the inside. This shape and configuration of the frame is very pleasing to the eye.

I am aware that the horseshoe shape is very common in articles of jewelry, in articles of

ornament, and in devices for ordinary household use, and I merely claim said shape in its special relation to voltaic-battery frames.

Having thus described the shape and configuration of this device, I claim—

The design for a horseshoe-shaped frame, A, B, C, b, and c, as herein shown and described.

In testimony that I claim the foregoing I have hereunto set my hand, this 15th day of May, 1884, in the presence of witnesses.

JAMES E. EVANS.

Witnesses:

HENRY J. HARROP,
WALTER ALCOKE.
